UNITED STATES PATENT OFFICE.

LOUIS POTTHOFF, OF MONTCLAIR, NEW JERSEY, AND GEORGE W. SCHWEINSEBERG, OF BROOKLYN, NEW YORK; SAID SCHWEINSEBERG ASSIGNOR TO SAID POTTHOFF.

ELECTROPLATING APPARATUS.

1,251,569.

Specification of Letters Patent.

Patented Jan. 1, 1918.

Application filed May 12, 1917. Serial No. 188,692.

To all whom it may concern:

Be it known that we, LOUIS POTTHOFF and GEORGE W. SCHWEINSEBERG, citizens of the United States, residing at Montclair, in the county of Essex and State of New Jersey, and Brooklyn, in the county of Kings and State of New York, respectively, have invented certain new and useful Improvements in Electroplating Apparatus, of which the following is a specification.

This invention relates to electroplating apparatus and particularly to a machine wherein the articles to be plated are moved through the electrolyte.

15 The object of the invention is to provide apparatus whereby the articles will be carried through the plating solution in a closed path returning the plated articles to the point of supply so that a single operator can 20 place the work on the carrier and remove it when finished. In the usual electroplating tank the articles are carried therethrough in one direction and two operators are necessary, one to place the articles on the 25 conveyor, and the other to remove them at the opposite end of the tank. By this invention, one workman can both place the articles in the machine and attend to the removal of the plated product.

30 A further object of the invention is to provide apparatus which will be simple in construction and adapted to handle a wide variety of work. In the machine of this invention a single conveyor carries the work 35 through the plating solution. Along this conveyor the articles may be spaced in any desired manner to maintain the total plating area necessary for efficient action. The articles being plated may also be left on the 40 conveyor any desired length of time before removal so that the coating can be continued until a deposit of any desired thickness is built up. The apparatus will, therefore, readily adapt itself to a wide variety of work 45 and maintain efficient plating conditions at all times.

In the accompanying drawings, Figure 1 is a plan view of electroplating apparatus embodying this invention;

Fig. 2 is a longitudinal sectional elevation, 50 and

Fig. 3 is a cross-section on the line 3-3 of Fig. 2.

In the drawings, one specific embodiment of the invention is shown wherein 1 is the 55 tank containing the electroplating solution to a height indicated approximately at line 2 of Fig. 3. Extending along the tank and supported by brackets 3 adjustable in slots 13 of cross bars 12 are anode rods 4 on which 60 are removably suspended anodes 5, the current being distributed to these anodes by conductor strips 14 from terminals 51. Between the anodes and above the surface of the solution is the cathode rail 6 formed by 65 bars 7 connected at both ends by semi-circular bars 8 and 9 to provide a continuous track of conducting material. This rail is connected to cathode terminal 52 and is supported by cross strips 10 suspended by 70 brackets 11 from cross bars 12.

The articles to be plated are moved through the solution by a continuous carrier chain 15 comprising links 16 provided with hooks 17 from which the articles are suspended to hang immersed in the plating solution. The hooks 17 are slidably supported on the rail 6 and as they support and convey the articles they conduct the plating current from the articles to the rail so that the electroplating circuit is from one side of the 75 supply line connected to anode bars 4 to anodes 5, through the articles to hooks 17 to track 6 connected to the other side of the line. To retain the hooks 17 in place on 80 track 6 their bases are provided with flanges 18 and 19 engaging respectively with the inner edges of track 6 and an upper rail 20 supported from brackets 29 of cross bars 12 by springs 30 resiliently pressing the hooks 85 against track 6. The hook shanks are bent around underneath the chain as shown in order to position the supporting ends of the hooks directly under the track 6 so that the centers of gravity of the supported articles 90 or baskets will be in a vertical line with the track and will not tend to tip the hook support on the track.

To move chain 15 and carry the suspended articles through the solution sprocket wheels 21 and 22 are provided. These wheels 21 and 22 are rigid on upright shafts 23 and 24 concentric with semi-circles 8 and 9 and journalled in brackets 25 and 26 carried by cross beams 27 and 28, respectively. The shaft 24 of driving sprocket 22 has fastened to it worm wheel 31 rotated by worm 32 on shaft 33 driven in any suitable manner as by chain 34 between sprocket 35 and overhead sprocket 36. The rate of movement of the carrier chain may be made variable and is sufficiently slow to permit the articles to be readily removed and replaced. The cross beam 27 supporting shaft 23 of idle sprocket 21 is adjustable along the tank by screws 37 to take up slack in the chain 15. In order to keep the plating solution constantly stirred, the shafts 23 and 24 may carry at their lower ends propeller blades 38. Stirring beams 39 are also provided carried by brackets 40 pivoted at 41 to the sides of the tank. These beams are oscillated around pivots 41 by any suitable means as rod 42 attached at its upper end to a crank arm of the overhead counter shaft and at its lower forked ends 43 to the beams 39.

In operation, the workman after turning on the power to drive endless conveyer or carrier chain 8, stands at any part of the machine as at end 50, and hangs the articles or baskets carrying the articles on the hooks 17 as they pass. Normally the time of travel of the carrier is so adjusted with relation to the rate of plating that the articles will be just sufficiently plated when they have completed one trip around the tank and returned to the point of supply. Here the operator removes the finished products and replaces them by other pieces to be plated. With many kinds of work a single operator can supply the carriers of several machines whereas in former tanks, where the conveyer moves only in one direction, an operator was necessary at each end of the tank.

The spacing of the articles or baskets along the endless conveyer may be varied to regulate the total surface plating at one time so that the solution strength and the current may be used most efficiently for each lot of articles. The length of the tank will be determined by the rate of movement of the carrier and the character and the depth of the deposit but, since the articles may be removed at any point of their trips around the tank, wide control of the coating is possible by varying the length of time the articles are permitted to remain in the solution. The articles being plated are always accessible for removal and inspection and may be readily replaced in position. The arrangement of the parts of this machine

is such as to permit the construction to be 65 simple, strong and durable, largely composed of standard parts and easily accommodated to different sizes of tanks.

It is apparent that the rate of travel of the carrier may be made variable, that the 70 chain links may be provided with rollers to reduce frictional resistance, and that the size and proportions of the parts of the apparatus may be varied widely to suit different plating conditions. The invention is not 75 confined to the specific embodiments shown herein, but is intended to cover such modifications thereof as come within the scope of the appended claims.

Having thus described our invention, we 80 declare that what we claim as new and desire to secure by Letters Patent, is:—

1. In electroplating apparatus, the combination with a tank for containing the electrolyte, of an endless linked chain adapted 85 to convey the articles to be plated in a closed path in said tank, a single rail track for supporting said chain and slidably fitted to the links thereof, and hook members carried by the links of said chain and adapted 90 to support the articles to be plated clear of said track.

2. In electroplating apparatus, the combination with a tank for the electrolyte, of an endless linked chain adapted to convey the 95 articles to be plated through said tank, a track for supporting said chain and slidably fitted to the links thereof, hook members carried by the links of said chain and adapted to support the articles to be plated 100 clear of said track, and resilient guides for yieldingly pressing the links of said chain against said track.

3. In electroplating apparatus, the combination with a tank for the electrolyte, of an 105 endless conveyer moving the articles through said electrolyte and comprising links having vertical and horizontal bearing surfaces, a track supporting said conveyer and slidably fitted to horizontal and vertical bearing 110 surfaces of said links, a guide strip engaging said links and retaining them in place on said track, and article supporting members carried by said conveyer.

4. In an electroplating apparatus, the 115 combination with a tank for the electrolyte, of a movable conveyer for suspending the articles to be plated in said electrolyte and moving them in series through said tank, a series of anodes in said tank parallel to the 120 line of movement of said articles, agitating means for the electrolyte comprising a longitudinal, pivoted bar member near the bottom of said tank and substantially parallel to said anodes, and means for vertically 125 oscillating said bar back and forth beneath the anode surfaces to cause movement of the electrolyte between said articles and said

anodes and across the line of feed of said articles, so as to renew the electrolyte and penetrate the recesses of said articles.

5. In electroplating apparatus, the combination with a single track, of a conveyer on said track for moving the articles through an electrolyte, and hooks rigid with the conveyer for supporting the articles to be plated so that their centers of gravity are in a vertical line below said track.

6. In electroplating apparatus, the combination with a cathode track, a conveyer for moving the articles along said track, and article supporting hooks on said conveyer reenteringly bent back underneath said track and held against pivotal movement in a plane normal to said track.

LOUIS POTTHOFF.
